(57) CLAIM

The ornamental design for a cowboy boot cork holder, as shown and described.

DESCRIPTION

FIG. 1 is a front, top and right side perspective view of a cowboy boot cork holder showing my new design; FIG. 2 is a back, bottom and left side perspective view thereof;

FIG. 3 is a right side view thereof; and, FIG. 4 is a left side view thereof.

The broken lines shown indicate unclaimed portions of the cowboy boot cork holder and form no part of the claimed design.
